US00D453347S

(12) **United States Design Patent** (10) Patent No.: **US D453,347 S**
Kaneko et al. (45) Date of Patent: ** Feb. 5, 2002

(54) **SWITCHING ASSEMBLY FOR FLUID PRESSURE APPARATUS**

U.S. application No. 29/121,921, filed Apr. 18, 2000, pending.

(75) Inventors: **Ryushiro Kaneko; Shinji Miyazoe**, both of Ibaraki (JP)

* cited by examiner

(73) Assignee: **SMC Corporation**, Tokyo (JP)

Primary Examiner—Antoine Duval Davis
(74) Attorney, Agent, or Firm—Oblon, Spivak, McClelland, Maier & Neustadt, P.C.

(**) Term: **14 Years**

(57) **CLAIM**

(21) Appl. No.: **29/121,914**
(22) Filed: **Apr. 18, 2000**

The ornamental design for a switching assembly for fluid pressure apparatus, as shown and described.

(30) **Foreign Application Priority Data**

Oct. 18, 1999 (JP) 11-28501

(51) LOC (7) Cl. **15-09**

(52) U.S. Cl. **D15/143; D15/5**

(58) Field of Search D15/5, 143; 74/89.15,

74/490.09; 92/5 R, 13.5, 88, 117 A; 310/20,

80

(56) **References Cited**

FIG. 1 is a top and right front perspective view of a switching assembly for fluid pressure apparatus, showing our design;

FIG. 2 is a top and left rear perspective view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a left side elevational view thereof; and,

FIG. 8 is a right side elevational view thereof.
